UNITED STATES PATENT OFFICE.

GEORGE G. FRELINGHUYSEN, OF MORRIS COUNTY, NEW JERSEY, ASSIGNOR TO STEEL UTILITIES, INCORPORATED, A CORPORATION OF NEW YORK.

METHOD OF DATING COMMODITY-PACKAGES.

1,289,432.

Specification of Letters Patent.

Patented Dec. 31, 1918.

Original application filed October 11, 1916, Serial No. 125,120. Divided and this application filed February 15, 1918. Serial No. 217,333.

To all whom it may concern:

Be it known that I, GEORGE G. FRELINGHUYSEN, a citizen of the United States, and a resident of Morris county, in the State of New Jersey, have invented new and useful Improvements in Methods of Dating Commodity-Packages, of which the following is a specification.

The invention relates to a new method of dating commodity packages whereby the manufacturer will have a permanent record upon such commodity packages of the dates when filled. The objects and advantages of the present invention will be set forth in part hereinafter, and in part will be obvious herefrom, the same being attained through the various steps and succession of steps pointed out in the appended claims.

The invention consists in the novel method, steps and improvements herein shown and described.

This application is a division of my application Ser. No. 125,120, filed October 11, 1916.

The accompanying drawings, herein referred to, and constituting a part hereof, illustrate one embodiment of the invention, and together with the description serve to explain the principles thereof.

Of the drawings:—

Figure 1 is an end elevation of a machine which may be employed in practising the invention;

Fig. 2 is a section on the line A—B of Fig. 35 1; and;

Figs. 3 and 4 illustrate labels which are the product of the method or process of the present invention.

In packaging many commodities it is desirable for the manufacturer or purveyor to mark the package with the date of filling and sealing, and it is frequently desirable to do this by placing a chronological mark on a label applied to the package, and this is especially desirable in the cases of fluid, semi-fluid and other commodities which are packaged in bottles, tins and the like. It is also frequently desirable that this chronological or dating mark be decipherable or legible only by the manufacturer or purveyor and that it be unnoted or not understood by consumers of the commodity. With certain lines of merchandise universally decipherable dating by perforating the numerals of

the day of month and year in the label is 55 objectionable, as consumers are thereby frequently groundlessly prejudiced against commodities.

It is further desirable that the dating marks in addition to being undecipherable 60 by the consumer shall be unobtrusive or practically unnoticeable to the casual observer of the label. Many commodities are packaged with artistic and ornamental labels affixed, which have great value in enhancing the attractiveness and desirability of the goods and increasing the demand among consumers for the particular brand, and the present invention dates the labels so as to preserve their attractiveness for the purposes stated.

It is also an object of the present invention to provide in connection with the foregoing, a method of dating the labels which will produce a label adapted for rapid, easy 75 and reliable handling in connection with the affixing thereof to the commodity packages. It has been the practice to date labels by punching or perforating numerals there-through corresponding to the month, day 80 and year, but this is objectionable because it causes adjacent labels to stick together and thus interferes with and stops the label affixing machine, causing a waste of both time and labels. Furthermore, this old way of so 85 marking the labels is tedious and expensive, as the labels can be punched only in small groups or bunches, and the punches are rapidly dulled and must be frequently replaced, all of which is obviated by the present 90 method.

By means of the method or process of the present invention, the labels may be marked in packs or bundles of thousands, the marking of a group of one or more thousands of 95 labels consuming very little labor, and sufficient labels for the daily output of even the largest factories may be thus chronologically marked in a few minutes of time. Further by this invention the marking of 100 the labels does not cause them to stick together, also there is but little wear on the marking mechanism and when desired the mark may be undecipherable by the consumer.

105 Referring to the accompanying drawings, illustrating by way of example one manner of practising the invention is shown in con-

nection with a machine, although it will be understood that the invention may also be practised manually and independently of any machine or mechanism. In the drawings, the labels α , which may number hundreds of thousands, are firmly clamped together in a carrier, and when so clamped their edges are indented at selected places or points corresponding to months and days of the month. As shown, the labels α are of irregular conformation although rectangular or circular or other shaped labels may be employed if desired. The label holder comprises end plates 1 and 2, to one of which is attached a side and bottom support 3. The other end plate is shaped to pass within the support 3, so that groups of labels varying widely in number may be held in the carrier and marked.

20 The plates 1 and 2 of the carrier are movable from each other to receive the labels α and are movable toward each other to firmly press together and hold the labels for marking. In the embodied form, the end plates 25 1 and 2 are provided respectively, with internally screw-threaded bosses 4 and 5, which bosses are in threaded engagement with a right-hand and left-hand screw-threaded shaft 6. When the shaft 6 is turned in one direction, the plates 1 and 2 recede from each other and when the shaft 6 is turned in the other direction, plates 1 and 2 approach each other and press together and firmly hold the labels α . The end plates 1 and 2 30 have at their bottoms projections 7 and 8, which enter into and travel along a groove 9 in a bed plate 10 of the machine. The shaft 6 is conveniently provided with a handwheel 11 for turning it in either direction. The shaft 6 is rotatably journaled in 35 bearings 12 and 13 formed on the machine frame, and is longitudinally slid able or reciprocable in its bearings to feed the labels past the marking device.

40 The embodied form of marking device 45 comprises a rotating miller or saw 14, mounted on a shaft 15 of a motor 16, the saw 14 being preferably within a safety casting 17.

50 Means are provided for relatively positioning the marking device 14 and the gang of labels α in accordance with the day and month to be marked on the label. In the embodied form of such means, the motor 16 55 is slid able (to the right and left in Fig. 1) upon a table 18, which table is carried upon a bracket 19 fixed to the machine frame. The base 20 of the motor is formed to slide upon the table 19 and has a portion projecting into a grooved guideway 21 in the 60 face of the table 19. Projecting downwardly from the base 20 is an internally screw-threaded lug 22. The lug 22 is in threaded engagement with a screw shaft 23, 65 which shaft is journaled in supports 24 and

25 formed on the underside of the table 18. The screw shaft 23 may be provided with a handle 26.

Chronological indications are provided for indicating the position of the marking device 14 relatively to the labels in the holder. With the form of label shown, it is convenient to indicate the date by secret marking at the edges a , b , c and d of the labels, the marking being also preferably in 70 definite predetermined positions with respect to the lettering or descriptive matter or other markings on the package. Thus any one of four points or positions along the edge a may be selected for notching, 75 and may be used for the first four months of the year. Four similar points or positions at the edge b may be used and may be selected for the succeeding four months of the year, and four points or positions at the 80 edge c may be used, and selected when needed, for the remaining four months of the year. A notch selectively placed at any one of these positions would indicate the month of the year in which the commodity 85 was packaged. At the edge d would be four positions indicating the weeks of the month; thus two notches selectively placed in the edge of the label, one notch at the proper point in either of edges a , b or c , 90 and the other notch at the proper point in edge d would give the date of packaging within a limit of one week. It will be obvious that the arrangement of notches may be varied as desired to indicate the precise day 95 of the month, and also to indicate the year of packaging in like manner where this might be desirable.

If it is desired to keep the date secret from the consumer, there need be no typographical or other indications upon the label which would be ordinarily decipherable, while on the other hand if this should not be an object, numerals could be placed upon the label whereby the date could be read. If 105 desired, a master plate or index may be utilized by the manufacturer to read the secret marking of the labels, but usually in practice the labels can be read by the eye of one familiar therewith and knowing the 110 system of secret marking.

In the embodied form, as stated, the relative change of position between the marking device and the clamped labels for indicating the date is effected by moving the motor and marking device to the right and to the left in 115 Fig. 1. The chronological index in the present case comprises four marks 27 on the table 18, and a co-operating mark 28 on the base 20 of the motor 16. The four marks on 120 the table correspond to the points or positions on the edges of the label for days, weeks or months, and the mark 28 corresponds to the selected date which will be marked by the marking device. The mark- 125 130

ing device 14 may be accurately positioned by turning the handle 26 of the screw shaft.

The shaft 6 is drawn forward or back so that the labels clamped in the carrier may be 5 clear of the marking device, say to the right in Fig. 2, as the shaft is slideable in its bearings 12 and 13. Shaft 6 is rotated to move plates 1 and 2 away from each other so that the gang or package of labels α may be 10 placed within the carrier. Shaft 6 is then rotated in the opposite direction to press plates 1 and 2 together and so firmly hold the gang of labels α . The motor 16 is started, and the shaft 6 is moved longitudinally, sliding in its bearings 12 and 13, and carrying the plates 4 and 5 with the gang of labels, to feed the labels past the marker 14, thereby marking them at the selected chronological point.

20 From all the foregoing it will be understood a new label has been provided, and a new system or method of dating commodity packages. It will be understood, also that changes may be made from the exact manner of practising the invention herein shown and described without departing from the principles of the invention and without sacrificing its chief advantages.

What I claim is:—

30 1. The method of dating commodity packages which comprises placing a secret chronological mark thereon in arbitrary position known only to the packager.

2. The method of dating commodity packages which comprises placing a plurality of arbitrary marks thereon in predetermined relation with respect to each other to indicate the month and day of packaging.

3. The method of dating commodity packages which comprises placing a secret chronological mark thereon in arbitrary position with respect to the lettering or other markings on the package.

4. The method of dating commodity packages which comprises placing a plurality of arbitrary marks thereon in predetermined relation with respect to the markings on the package to indicate the month and day of packaging.

50 5. The method of dating commodity packages which comprises placing a plurality of arbitrary marks thereon in predetermined relation with respect to each other and to the markings on the package, to indicate the month and day of packaging.

6. The method of dating commodity pack-

ages which comprises placing a secret dating mark in predetermined position on a label to indicate a date and attaching the dated label to a commodity package on that date.

7. The method of dating commodity packages which comprises placing a secret dating mark in predetermined position on the edge of a label to indicate a date and attaching the dated label to a commodity packaged on 65 that date.

8. The method of dating commodity packages which comprises placing a secret dating mark in predetermined position with respect to the lettering on a label to indicate a date 70 and attaching the dated label to a commodity packaged on that date.

9. The method of dating commodity packages which comprises taking a gang of labels and placing a secret dating marking 75 in predetermined position in each label of the gang of labels to indicate a particular date and applying the labels to commodity packages filled on that date.

10. The method of dating commodity 80 packages which comprises taking a gang of labels simultaneously placing on each label of the gang of labels a plurality of secret dating marks in predetermined relation to each other to indicate a particular date and 85 applying the labels to commodity packages packaged on the marked date.

11. The method of dating commodity packages which comprises taking a gang of labels and marking the edges of the labels 90 with arbitrary marks in predetermined relation to each other to indicate a particular date, and applying the various labels to commodity packages packaged on the marked date.

12. The method of dating commodity packages which comprises placing a mark thereon in a position indicating the date of packaging the commodity.

13. The method of dating commodity 100 packages which comprises placing a plurality of marks thereon, the location of the marks indicating the date of packaging the commodity.

In testimony whereof, I have signed my 105 name to this specification, in the presence of two subscribing witnesses.

GEORGE G. FREILINGHUYSEN.
